RAYON SPINNING MACHINE FUNNEL
BRACKETHenry James McDermott, Prospect Park, Pa.,
assignor to American Viscose Corporation,
Marcus Hook, Pa., a corporation of Delaware

Application August 6, 1938, Serial No. 223,483

16. Claims. (Cl. 57—76)

This invention relates to a bracket for carrying the funnel of a spinning machine adapted to make rayon yarn by the pot spinning method. In such machines the yarn is brought into the 5 pot through a funnel which reciprocates vertically with its supporting rails, in order to form the yarn "cake". The funnel must be put out of the way to permit removal of the completed yarn cake.

10 The invention relates to an improved bracket which facilitates getting the funnel out of the way for removal of the cake. More particularly it provides means for retracting a funnel having a long stem without detaching the funnel from the 15 bracket.

When doffing or removing the rayon cake from the spinning pot, the present practice is to remove the funnel from the bracket and place it in a rack on the spinning machine. This is usually done by hand. Very often in this operation 20 the funnel is broken. An advantage of the novel device is that it does away with the necessity for workmen to handle the funnel in retracting it from a spinning box and thus eliminates this 25 breakage. Mechanical means have heretofore been provided for this purpose but they have not been satisfactory.

In the modern pot spinning machine it is necessary to keep the pot as completely closed as 30 possible, and therefore to have the hole for the funnel as small as possible. In addition the space available for movements of the funnel bracket is quite restricted. For the relatively long funnels now used, the prior art provides no 35 satisfactory means of moving the funnel or the bracket.

In the accompanying drawings which form a part of the specification:

40 Figures 1 to 5 inclusive are side elevations showing the novel funnel lifting bracket;

Figure 1 shows the bracket holding a funnel in its lowest or operating position, parts being broken away to show details;

45 Figure 2 shows a bracket in a position in which the funnel has been slightly elevated by the bracket;

Figure 3 shows the bracket in a more elevated position, having withdrawn the funnel from the spinning pot;

50 Figure 4 shows the bracket in its most elevated position and holding the funnel out of the way of the spinning pot;

Figure 5 is an elevation similar to Figure 1, but 55 on a smaller scale, showing the novel bracket and

the funnel in relation to other parts of a spinning machine;

Figure 6 is a top plan view of Figure 1;

Figures 7, 8 and 9 show a modified form of the invention, parts being broken away to show details; Figure 7 shows the bracket in its lowest or operating position; Figure 8 shows the bracket in a position which it assumes soon after the tube of the funnel has escaped from the lid; Figure 9 shows the bracket in its most elevated position 10 and holding the funnel out of the way of the spinning pot;

Figures 10, 11 and 12 show another modified form of the invention, with the parts in positions corresponding to those shown in Figs. 7, 8 and 9 15 respectively.

Further describing the embodiment of the invention illustrated in Figures 1 to 6, the principal parts of the novel bracket are a funnel support 11, a pair of links 12 and 13 of unequal length and a 20 crank 14. The bell crank lever 14 rocks about a pivot 15, while link 12 swings on a pivot 16, which may be considered the pivot of the bracket taken as a whole.

One arm 17 of crank 14 is pivoted at 18 to link 25 13. The other arm 19 (see Figs. 3 and 4) which is illustrated as the shorter arm bell crank 14, is provided with a pin 20 which cooperates with a cam on link 12. As illustrated in Figure 1 this is a three direction cam and is provided by guiding 30 walls of a slot 21 in link 12, but it is obvious that it could be provided by other suitable means.

Funnel support 11, at the distal or free end of the bracket, may comprise a link between links 12 and 13. Link 11 may comprise a base 35 22 on which rests a usual funnel 23, trunnions 24 which are shown as substantially in alignment with an axis of funnel 23 (see Figs. 5 and 6); and an upwardly and rearwardly projecting boss or arm 25, to which link 13 is pivoted at 26. As 40 shown in Figure 1, the funnel-support 11 is substantially L-shaped in elevation, but the shape is optional.

Link 12, which may be considered the funnel-lifting link, is pivoted to link 11 at 24, substantially on a line through the center of the funnel 23, and considerably below and in front of the point 26 at which the link 13, which may be considered the funnel-tilting link, is pivoted to the 45 funnel-supporting link 11. In other words, pivot 26 is not in the same plane as the axis of funnel 23 with which pivot 24 is aligned.

The funnel-lifting element is a single link 12 having a pair of arms 27 which receive the trun-

nions 24 of link 11 (see Fig. 6), but this arrangement is optional.

As shown in Figures 5 and 6, the novel bracket is supported just above and to the rear of the spinning pot 28 and its cover 29, on the usual rails 34. The pivot 15 of the crank lever 14 is supported by a bracket 30 and the pivot 16 of the funnel-lifting link 12 is supported by a bracket 31, attached by means such as cooperating jaws 32 and 33 to the rails 34 on a spinning machine. Any suitable means such as a set screw 37 (see Figs. 1, 5 and 6) may be provided to determine the down position of the bracket. The set screw 37 in link 12 cooperates with a portion of the jaw 32 to limit the link's down position. The upper position of the link is limited by its end portion which engages the bracket 31 when it is lifted to its upper limit. This prevents the pin 20 from striking the end of the cam slot at R, 20 as shown in Figure 4.

When the funnel 23 is in the operative or spinning position with its tube 35 reciprocating vertically through the opening 36 of the cover 29 of the spinning pot, the bracket is in the position 25 shown in Figures 1 and 5. As already mentioned it is desirable to have the opening 36 as small as possible, and on the other hand the tube 35 is preferably relatively long. For instance, in a device where the inside distance from the bottom of the box 28 to the top of its cover 29 is $7\frac{3}{4}$ inches, and the diameter of the opening 36 in the pot cover is only $1\frac{1}{8}$ inches, a funnel having a stem $8\frac{1}{8}$ inches long from its tip to the center of the trunnion 24, for example, may be employed by 35 using the present invention. It is to be understood that these dimensions are by way of example only, and are not intended to limit the scope of the disclosure.

When it is desired to remove the funnel to its 40 inoperative position clear of the spinning pot 28, the funnel mounting 11 is lifted causing the link 12 to pivot about the point 16. In moving from operative to inoperative position link 12 moves upward in an arcuate path counterclockwise as 45 illustrated in these drawings. (It will be obvious that the terms "clockwise" and "counterclockwise" are relative terms, and that if the machine were viewed from the opposite side, or the figures reversed, the relative motion, and therefore the 50 terms, would be reversed.) This motion causes a collapsing of the side of the bracket between pivots 16 and 18. Pin 20 moves from its position at the top of slot 21 (see Figs. 1 and 5) downward along cam 21. To remove a relatively long tube 55 35 of the funnel 23 from the spinning pot through the relatively small central opening 36 in the cover member, the funnel 23 must be tipped to compensate for the horizontal component of movement caused by the counterclockwise rotation of link 12. Clockwise tipping of funnel 23 about the pivot 24 (see Fig. 2) is effected during the first part of the movement by the portion x, y of the cam 21. Movement of pin 20 downward through this portion of the cam causes the crank 60 14 to pivot about point 15 in a counterclockwise direction and acting through the link 13, causes the funnel mounting 11 to tip about the points 24 and 26 so that funnel 23 is tipped in a clockwise direction around point 24 (see Fig. 2). The 65 next portion y, z of the cam 21 is concentric with 16 of the bracket, so the movement of pin 20 through the part y, z of cam 21 does not materially affect the movement of the funnel. During this part of the movement, tube 35 of the funnel 70 23 moves in a large arc counterclockwise in the

arc of the link 12 around the point 16, the tube 35 below the point 24 moving forward and upward to escape from the opening 36.

By the time the pin 20 reaches the position z , of the cam 21, the entire funnel has been removed from the closed pot 28 and its cover 29 (see Fig. 3). Continued movement of the bracket mounting brings pin 20 into engagement with portion z, r of cam 21. This tilts the bell crank 14 in a clockwise direction (Fig. 4), and acting 10 through link 13 swings the funnel 23 in a clockwise direction about the point 24 and to a position clear of the spinning pot 28, so that cake 38 (Fig. 4) can be removed therefrom.

Thus the continuous rotation of the novel 15 bracket in a counterclockwise direction about its main pivot 16 causes the base 22 of the funnel-supporting link 11 and the funnel 23 to rotate counterclockwise about the point 16, and simultaneously to travel about the point 24 in a three 20 directional movement first clockwise, then counterclockwise and finally clockwise again, before the funnel 23 comes to rest in a position (see Fig. 4) above and behind the spinning pot 28. Thus it will be seen that in Figs. 1 to 6 the crank 14 25 and its pin 20, together with the cam means associated with lifting link 12, constitute control means to give the funnel 23 and the funnel support 11 a path of travel about the axis 24, distinct from their path of travel around the main 30 pivot 16 of the bracket, whereby the portion of the funnel tube 35 passing out of the top of the pot is kept within the small area of the hole 36 in the pot cover 29, regardless of the position of the distal end of lifting link 12.

In returning the funnel to spinning position the operations and movements just described are reversed.

Figures 7, 8 and 9 show a modified form of the invention, in which the novel bracket after passing 40 through approximately the positions shown in Figures 1, 2 and 3, swings the stem 35 forwardly and upwardly out of the way of the cover 29 of the pot 28 (see Fig. 9) instead of swinging the stem 35 to the position shown in Fig. 4.

In this modification a crank 114 rocks about a pivot 115 and there is a link 113 pivoted to the crank at 118. Crank 114 carries a pin 120 which cooperates with a cam slot 121 associated with link 112. In moving from operative position shown in Fig. 7, to withdrawn position shown in Fig. 9, link 112 moves upward counterclockwise as illustrated in these figures. This causes the pin 120 to move from its position at the bottom of slot 121 upward along cam 121 from a to b . Clockwise tipping of funnel 23 about the pivot 124 is effected during this part of the movement by the portion a, b of the cam slot 121, as is perhaps best shown by Fig. 8. Further movement of link 112 upward about the pivot point 116 causes teeth 140 associated with link 112 to mesh with teeth 141 carried by the portion 119 of crank 114. This results in movement of the tube 35 of the funnel 23 counterclockwise about the pivot 124 so that after the tube has escaped from the opening 36 in the cover 29, it swings up and forward out of the way of the lid 29, as shown in Figures 8 and 9.

In Figure 8, f^1 to f^{10} indicate a series of positions of the end of the funnel 35 in its path of travel from spinning position, to the withdrawn position. Corresponding positions of points 124 and 126 are shown at g^1 to g^{10} and h^1 to h^{10} respectively.

Figures 10, 11 and 12 show a further modifica- 75

tion in which the stem 35 swings forwardly and upwardly out of the way, as it does in Figures 7, 8 and 9. In these figures link 212 is provided with a modified cam 221.

5 The embodiments of the invention shown and described are illustrative only. Other embodiments will occur to those skilled in the art.

I claim:

1. A funnel lifting bracket for a spinning machine comprising a pair of links, and a third link for supporting a funnel and pivoted to each of said first named links, in combination with a crank also connecting said first named links, and cooperating eccentric means associated respectively with one of said first named links and with an arm of said crank, to control the path of travel of the funnel.

2. A funnel lifting bracket for spinning machine comprising in combination, funnel-supporting means, a funnel-lifting link pivoted thereto and pivoted at its other end to a support, a cam in conjunction with said funnel-lifting link, a crank cooperating with said cam, a funnel tilting link pivoted at one end to said funnel-supporting means and pivoted at the other end to said crank.

3. A funnel lifting bracket comprising a pair of links, of unequal length, a pivotal support for said bracket adjacent an end of the longer link, and a connecting link pivoted adjacent the other ends of said pair of links in combination with a bell crank having an arm pivoted to one link of said pair and cooperating eccentric means associated respectively with the other arm of said

25 crank and the other link of said pair.

4. A funnel lifting bracket comprising a pair of links of unequal length, a pivotal support for said bracket adjacent an end of one of said links, and a connecting link pivoted adjacent the other ends of said pair of links in combination with a bell crank lever having arms of unequal length and having its longer arm pivoted to the shorter of said pair of links, and cooperating eccentric means associated respectively with the other arm 45 of said crank and the other link of said pair.

5. A funnel lifting bracket comprising a pair of links, a pivotal support for said bracket adjacent an end of one of said links, and a connecting link pivoted adjacent the other ends of said pair of links, 50 said connecting link having a pivot point with one of said pair of links substantially on an axis of said funnel, and having its pivot with the other link outside of said axis, in combination with a crank pivoted to one of said pair of links, 55 and cooperating eccentric means associated respectively with said crank and the other link of said pair.

6. A funnel lifting bracket for spinning machine comprising in combination, a substantially L-shaped funnel-support having a base and an arm, a funnel lifting link pivoted adjacent one end to said support and being pivotally supported at its other end, a slotted cam in conjunction with said funnel lifting link, a crank cooperating with said cam, and a funnel tilting link pivoted at one end to the arm of said funnel support and pivoted at the other end to said crank.

7. A funnel lifting bracket comprising a support, a funnel-lifting means pivoting upon said support and adapted to lift a funnel counterclockwise about said support, in combination with means for simultaneously moving the funnel alternately clockwise and counterclockwise about an axis, said second means comprising funnel-

tilting means, funnel-supporting means linked between said funnel-lifting means and said funnel-tilting means, cam means associated with said funnel-lifting means, a crank pivoted to said funnel-tilting means and having means co-operating with said cam.

8. In a rayon spinning machine having a guide funnel, a spinning pot and an apertured cover for said pot, a funnel bracket comprising funnel-lifting means adapted to lift a funnel from the covered pot counterclockwise in the arc of said means, in combination with means for simultaneously moving the funnel alternately clockwise and counterclockwise about another axis substantially on an axis of the funnel.

9. In a rayon spinning machine having a guide funnel, a spinning pot and an apertured cover for said pot the aperture being of small diameter relative to the length of the funnel, a funnel bracket comprising funnel-lifting means adapted to lift a funnel counterclockwise in the arc of said means, in combination with means for simultaneously moving the funnel about another axis, alternately clockwise and then counterclockwise to withdraw the funnel from the aperture of the spinning pot.

10. In a rayon spinning machine having a guide funnel, a spinning pot and an apertured cover for said pot the aperture being of small diameter relative to the length of the funnel, a funnel bracket comprising funnel-lifting means adapted to lift a funnel counterclockwise in the arc of said means, in combination with means for simultaneously moving the funnel about another axis, alternately clockwise and then counterclockwise to withdraw the funnel from the aperture of the closed spinning pot and to a position clear of the spinning pot.

11. In a rayon spinning machine having a guide funnel, a spinning pot and an apertured cover for said pot the aperture being of small diameter relative to the length of said funnel, a funnel bracket comprising funnel lifting means adapted to lift a funnel counterclockwise in the arc of said means, in combination with means for simultaneously moving the funnel about another axis, alternately clockwise and then counterclockwise to withdraw the funnel from the aperture of the closed spinning pot, and then clockwise again to withdraw the funnel to a position clear of the spinning pot.

12. A funnel lifting bracket for a rayon pot spinning machine comprising a pair of links of unequal length and a third link carrying the funnel and pivoted to each of said first named links, in combination with a crank connected to said first named links, and cooperating eccentric means associated respectively with one of said first named links and with said crank to control the angle of the funnel.

13. A funnel bracket for rayon pot spinning machinery comprising a lifting link having a fixed pivot at one end, the funnel being swivelly carried on the other end in combination with collapsing means controlled by said link adapted to tilt the funnel whereby the portion of the funnel passing out of the top of the pot is kept within a small area regardless of the position of the end of the link.

14. A funnel bracket for rayon pot spinning machinery comprising a lifting link pivotally mounted at one end, the funnel being swivelly carried on the other end, in combination with means separately mounted but actuated by said link adapted to tilt the funnel both ways from the

vertical about the swivel point whereby the portion of the funnel passing out of the top of the pot is kept within a small area regardless of the position of the end of the link.

5 15. A funnel bracket for rayon pot spinning machinery comprising lifting means pivotally mounted at one end, and a funnel-supporting link swivelly carried on the distal end thereof, and tilting means pivoted to said supporting link, 10 in combination with eccentric means connecting said tilting and lifting means, whereby the por-

tion of the funnel passing out of the top of the pot is kept within a small area regardless of the position of the distal end of the lifting link.

16. In a rayon spinning machine, a funnel lifting bracket comprising a pair of links and means for swivelly supporting a funnel at one end of said links, in combination with means for varying the distance between the other ends of said links in varying positions of said bracket. 10

HENRY JAMES McDERMOTT.
